UNITED STATES PATENT OFFICE

130,268

DESIGN FOR A SLIPPER OR THE LIKE

Bennett C. Creed, Hinsdale, Ill., assignor to Creed & Stewart, Ltd., Aurora, Ill., a corporation of Illinois

Application September 29, 1941, Serial No. 103,547

Term of patent 3½ years

To all whom it may concern:

Be it known that I, Bennett C. Creed, a citizen of the United States, residing at Hinsdale, county of Du Page, State of Illinois, have invented a new, original, and ornamental Design for a Slipper or the like, of which the following is a specification, reference being had to the accompanying drawing, forming a part thereof.

I claim:

The ornamental design for a slipper or the like, as shown.

BENNETT C. CREED.
